(57) **CLAIM**

We claim the ornamental design for a robotic arm controller, as shown and described.

DESCRIPTION

FIG. 1 is an isometric view of a robotic arm controller in accordance with a first variant of the present disclosure; FIG. 2 is a front view of the robotic arm controller of FIG. 1;

FIG. 3 is a rear view of the robotic arm controller of FIG. 1; FIG. 4 is a first side view of the robotic arm controller of FIG. 1;

FIG. 5 is a second side view of the robotic arm controller of FIG. 1;

FIG. 6 is a top view of the robotic arm controller of FIG. 1; FIG. 7 is a bottom view of the robotic arm controller of FIG. 1;

FIG. 8 is an isometric view of a robotic arm controller in accordance with a second variant of the present disclosure; FIG. 9 is a front view of the robotic arm controller of FIG. 8;

FIG. 10 is a rear view of the robotic arm controller of FIG. 8;

FIG. 11 is a first side view of the robotic arm controller of FIG. 8;

FIG. 12 is a second side view of the robotic arm controller of FIG. 8;

FIG. 13 is a top view of the robotic arm controller of FIG. 8; and,

FIG. 14 is a bottom view of the robotic arm controller of FIG. 8.

The broken line portions are included to show environmental unclaimed subject matter only and form no part of the claimed design.
